Des. 185,766
Patented July 28, 1959

185,766

CHILD'S TOILET SEAT

Robert Manushkin, Chicago, Ill.

Application January 26, 1959, Serial No. 54,316

Term of patent 14 years

(Cl. D4—5)

Fig. 1 is a perspective view of a child's toilet seat showing my new design;

Fig. 2 is a front elevational view of the same;

Fig. 3 is a top plan view of the same; and

Fig. 4 is a rear perspective view.

I claim:

The ornamental design for a child's toilet seat, substantially as shown.
